UNITED STATES PATENT OFFICE

LOUIS KAPLAN AND GEORGE WEISS, OF CHICAGO, ILLINOIS

COIN-CONTROLLED MECHANISM

Application filed September 24, 1928. Serial No. 307,873.

In our copending application, Serial No. 307,872, filed September 24, 1928, there is shown and described an improved vending machine whereby under predetermined conditions a cushion or cover for a seat, in connection with which the machine is employed, may be vended or delivered for use, the cushion or cover being returned to the machine after use, to be again vended under similar conditions.

The present invention, however, relates to an improved coin controlled mechanism, particularly adapted, though not necessarily limited in its use, in connection with such machines and one of the objects of the invention is to provide an improved coin controlled mechanism which will be extremely simple and compact in construction, durable, cheap to manufacture, and effective and efficient in operation.

To the attainment of these ends and the accomplishment of other new and useful objects as will appear, the invention consists in the features of novelty, in substantially the construction, combination and arrangement of the several parts, hereinafter more fully described and claimed and shown in the accompanying drawings illustrating this invention, and in which

Figure 1 is a vertical sectional view taken on line 1—1, Figure 2, of mechanism of this character constructed in accordance with the principles of this invention, with parts broken away and with parts omitted.

Figure 2 is a vertical sectional view taken on line 2—2, Figure 1.

Figure 3 is a view similar to Figure 2 with parts omitted and showing the parts of the mechanism in a different position.

Figure 4 is a view similar to Figure 5 with the parts in a different position.

Figure 5 is a detail sectional view taken on line 5—5, Figure 3.

Figure 6 is a view similar to Figure 7, showing the parts in a different position.

Figure 7 is a detail sectional view taken on line 7—7, Figure 3.

Figure 8 is a sectional view taken on line 8—8, Figure 3, with parts omitted.

Figure 9 is a view similar to Figure 7 showing the parts in a different position.

Referring more particularly to the drawings, the coin controlled mechanism is preferably arranged within a compartment 15 which is located within a container 16. The container may be of any desired size and configuration and is provided with an open top adapted to be closed by a closure 17, the latter being pivotally mounted as at 18. Extending across the container 16 is a shaft 19 and connected with the shaft, preferably on opposite sides of the container are catches 21, 21, which oscillate with the shaft. Each of the catches is provided with a shoulder 22 that is adapted to cooperate with a shoulder 23 on a catch 24, the latter being pivotally connected as at 25 with the closure 17. The catches 24 are loosely mounted upon the shaft 25 and secured to the shaft adjacent each of the catches is a collar 26. Between the collar 26 and the adjacent catch 24 is a spring 27 which is anchored by one end as at 28 to the collar 26, and is secured by its other end to the catch 24. The tendency of these springs 27 is to move the catches 24 in a direction that they will engage and cooperate with the shoulders 22 on the respective catches 20—21 when the closure 17 is closed. When, however, the closure 17 is open the catches 20—21 will be in locking position, and the operation of closing the closure will cause the catches 24 to swing about their pivots on the shaft 25, by reason of the ends of the catches 24 engaging the ends of the respective catches 20—21, to cause the catches 24 to yield so that they will move into the position shown in dotted lines in Figures 2 and 3. Secured to the shaft 19 is an arm 29 which is arranged within the compartment 15. A spring 30 engages the arm 29 and also a fixed support and tends normally to move the shaft 19 in a direction that the shoulders 22 on the catches 20, 21 will be in position to engage the shoulders 23 on the respective catches 24.

Mounted to slide in a suitable support and in a convenient position for the operator, is a member 31 which is provided with an operating button or handle 32 on the outside of the casing. One end 33 of the member 31

is preferably reduced, as shown in Figures 6 and 7, and the member 31 has connected with it a projection 34 extending laterally from the body portion thereof. Disposed beneath the member 31 is a coin supporting member 35 which is pivotally mounted as at 36 and is provided with a lateral projection 37. The projection, when the member 35 is in its normal position as shown in Figures 4 and 6, will be disposed beneath a coin chute 38^a, so that when a coin is delivered from the chute it will rest upon the projection or support 37 and will stand between the lateral projecting portion 34 of the member 31 and a portion of the arm 29, as indicated in dotted lines at 38 in Figure 3. The member 31 may be provided with a supporting surface 39 against which the coin 38 rests when it stands on its edge upon the support 37.

20. A spring 39^a is provided which engages and rests upon a projection 40 on the member 35, and also against a fixed support, and tends normally to move the member 35 to the position shown in Figures 4 and 6, that is with the support 37 in position to receive and support the coin 38.

When a coin is in the position shown in Figure 3, and the knob or button 32 is depressed or moved from its normal position as shown in Figures 2 and 6, to the position shown in Figures 3 and 7, the coin will form the connecting medium between the member 31 and the arm 29, by reason of the fact that the projection 34 engages the edge of the coin 38, and the coin in turn engages the arm 29. A pressure upon the knob or button 32 will then, through the medium of the arm 29, rock the shaft 19 to displace the catches 20, 21 to cause the shoulders 22 thereon to disengage the shoulders 23 on the respective catches 24 carried by the closure 17, to release the latter. A further movement of the member 31 in the same direction will cause the extremity of the portion 33 thereof to engage a projecting portion 40 on the member 35 to rock the latter from the position shown in Figures 4 and 6 to the positions shown in Figures 5 and 7, thereby withdrawing the support 37 from beneath the coin 38 to allow the latter to drop through an opening 41 into a check receptacle 42. The member 35 will be moved against the stress of the spring 39. When the button or knob 32 is released the spring 30 will return it to its normal position and at the same time the spring 39^a will return the member 35 to its normal position, or to the position shown in Figures 4 and 6.

10. A friction creating spring 43 may be provided for engaging a portion of the member 35, preferably a portion of the projection 40, to serve as a brake or means for creating a friction upon the member 35.

15. Thus it will be seen that when a check or coin 38 is delivered through the opening 44 in the front of the casing into the check chute

38^a, when the parts are in the position shown in Figures 2, 4 and 6, the check will drop upon the support 37. When the button or knob 32 is then pressed the closure 17 will be unlocked in the manner already described, after which the support 37 will be removed by swinging the member 35 to allow the check 38 to drop into the receptacle 42. The portion 33 of the member 31 is of such a length and the projection 40 on the member 35 is so located with respect of the end of the portion 33, that the closure 17 will be unlocked before the member 35 is shifted to release the coin or check.

20. Should there be no coin 38 present and resting upon the support 37, the arm 29 will not be rocked upon the operation of the member 31 and the closure 17 will remain locked.

25. The coin receptacle 42 may be of any desired configuration and pivotally mounted as at 45, and is provided with a projection 46 over which latter a bolt 47 of an ordinary key-controlled locking device 48 is adapted to be projected, so as to lock the receptacle 42 against pivotal movement.

30. A spring 49 may be provided which engages a projection 50 carried by the member 31 to return the member 31 and the operating knob or button to their normal position.

35. In order to protect the arm 29 from following back with the member 31 when the latter is released, which would cause the coin 38 to be gripped between the projection 34 on the member 31 and the arm 29, thereby preventing the coin from dropping out of position, any suitable means may be provided for temporarily locking or restraining the arm 29 against return movement until the coin 28 is released.

40. To that end there may be provided a catch 51 which is pivotally mounted as at 52 to swing about a vertical axis. This catch is provided with a shoulder 53 adapted to engage a shoulder 54 on the arm 29. A spring 57 is provided which tends normally to move the shoulder 53 into the path of the shoulder 54 on the return movement of the arm 29.

45. Carried by the member 31 is a pin or projection 55 which is adapted to co-operate at predetermined times in the cycle of operation of the member 31, with the cam shaped or inclined portion 56 on the catch 51. When the arm 29 is moved into the position shown in Figures 3 and 8, the spring 57 will move the catch 51 so that the shoulder 54 on the arm 29 will engage the shoulder 53 and thereby lock the arm 29 against return movement. When the parts are in the position shown in Figure 8, and when the knob or button 32 is released, the member 31 will be returned by the spring 33, but as the arm 29 is locked against return movement the member 31 will return in advance of the arm 29. When the pin or projection 55 on the member 31 engages the inclined portion 56 of the catch 51,

the catch will be moved about its pivot against the stress of the spring 57 so as to disengage the shoulder 53 from the shoulder 54. When the arm 29 is thus released the spring 30 will 5 return it and will position the catches 20—21 so that they will co-operate with the catches 24 when the closure 17 is closed.

In Figure 9 the catch 51 is shown in its normal position when the member 31 is returned and it will be noted that the pin or projection 55 co-operating with the cam or inclined portion 56 of the catch 51 will hold the latter in position that the arm 29 with the shoulder 54 thereon may be operated by 10 the member 31 when the coin 38 is in the machine and in the position shown in Figure 3.

Thus it will be seen that when the arm 29 is locked against return movement the 20 shoulder 34 on the member 31 will move out of engagement with the coin 38 and the latter will drop into the coin receptacle 42.

While the preferred form of the invention has been herein shown and described, it is to 25 be understood that various changes may be made in the details of construction and in the combination and arrangement of the several parts, within the scope of the claims, without departing from the spirit of this invention.

What is claimed as new is:—

1. Coin controlled mechanism embodying a locking device, an actuating member for said device, an actuator independent of said member, and a shiftable coin holder operating to position a coin between said member and said actuator whereby when said actuator is operated said member will be actuated to release said locking device, said coin holder 40 being responsive in its operation, at a predetermined time in the cycle of operation, to the operation of said actuator to release the coin.

2. Coin controlled mechanism embodying a locking device, an actuating member therefor, an actuator independent of said member, a shiftable member for holding a coin intermediate said actuating member and said actuator whereby a movement of said actuator 50 will operate said actuating member, and means whereby the operation of said actuator will, subsequent to the operation of said actuating member, operate upon the coin holding member to shift the latter to release the coin.

3. Coin controlled mechanism embodying a locking device, an actuating member therefor, an actuator independent of said member, a shiftable member for holding a coin intermediate said actuating member and said actuator whereby a movement of said actuator will operate said actuating member, means whereby the operation of said actuator will, subsequent to the operation of said actuating 60 member, operate upon the coin holding mem-

ber to shift the latter to release the coin, and means for returning the said coin holding member to its normal position upon the release of said actuator.

4. Coin controlled mechanism embodying a locking device, an actuating member therefor, an actuator independent of said member, a shiftable member for holding a coin intermediate said actuating member and said actuator whereby a movement of said actuator 70 will operate said actuating member, means whereby the operation of said actuator will, subsequent to the operation of said actuating member, operate upon the coin holding member to shift the latter to release the coin, and means individual to said actuating member, said actuator and said coin holding member for returning them to their normal position.

5. Coin controlled mechanism, embodying a locking device, an actuating member for said device, an actuator independent of said member, a shiftable coin holder operating to position a coin between said member and said actuator whereby when said actuator is operated said member will be actuated to release said locking device, said coin holder being responsive in its operation, at a predetermined time in the cycle of operation, to the operation of said actuator to release the coin, and means operating upon said coin holding member for yieldingly retarding its movement by said actuator.

6. Coin-controlled mechanism embodying a locking device, an actuating member therefor, an actuator independent of said member, a shiftable member for holding a coin intermediate said actuating member and said actuator whereby a movement of said actuator will operate said actuating member, means whereby the operation of said actuator will, subsequent to the operation of said actuating member, operate upon the coin holding member to shift the latter to release the coin, and means operating upon said coin holding member for yieldingly retarding its movement by the said actuator.

7. Coin controlled mechanism embodying a member to be actuated, an actuator independent thereof, a shiftable element, a portion of said element being adapted to assume a position to hold a coin between said member and said actuator, whereby the movement of the actuator will operate the said member, and means tending normally to move 115 said element in one direction, the said element being operable by said actuator to release the coin to render the actuator and said member ineffective with respect to each other, subsequent to the operation of said member 120 by said actuator.

8. Coin controlled mechanism embodying a member to be actuated, an actuator independent thereof, a shiftable element, a portion of said element being adapted to assume 130

a position to hold a coin between said member and said actuator, whereby the movement of the actuator will operate the said member, and means tending normally to move said element in one direction, a portion of said element being arranged in the path of movement of said actuator, to be engaged thereby, to shift said element to release the coin.

9. Coin controlled mechanism embodying a member to be actuated, an actuator independent thereof, a shiftable element, a portion of said element being adapted to assume a position to hold a coin between said member and said actuator, whereby the movement of the actuator will operate the said member, means tending normally to move said element in one direction, the said element being operable by said actuator to release the coin to render the actuator and said member ineffective with respect to each other, subsequent to the operation of said member by said actuator, and means for returning said member and said actuator to their normal position.

10. Coin controlled mechanism embodying a member to be actuated, an actuator independent thereof, a pivotally mounted element, and means tending to normally position a portion of said element to hold a coin in position between said member and said actuator, whereby operation of the latter will shift the former, a portion of said element being disposed within the path of movement of said actuator to be engaged thereby to shift said element against the stress of the said means, to release the coin.

11. Coin controlled mechanism embodying a member to be actuated, an actuator independent thereof, a pivotally mounted element, means tending to normally position a portion of said element to hold a coin in position between said member and said actuator, whereby operation of the latter will shift the former, a portion of said element being disposed within the path of movement of said actuator to be engaged thereby to shift said element against the stress of the said means, to release the coin, and friction creating means for yieldingly resisting the movement of said element in one direction.

12. Coin controlled mechanism embodying a member to be actuated, an actuator independent thereof, a portion of said actuator being arranged in alinement with but spaced from said member, a pivotally mounted element, a portion of said element adapted to assume a position to receive and hold a coin in the space between said member and said actuator to form a connection between the member and actuator whereby the latter will actuate the former, and a shoulder on said element adapted to be engaged and moved by one of the movable parts to shift said element to release the coin at a predetermined time in the cycle of operation of the device.

13. Coin controlled mechanism embody-

ing a member to be actuated, an actuator independent thereof, a portion of said actuator being arranged in alinement with but spaced from said member, a pivotally mounted element, a portion of said element adapted to assume a position to receive and hold a coin in the space between said member and actuator to form a connection between the member and actuator whereby the latter will actuate the former, and a shoulder on said element adapted to be engaged and moved by the said actuator to release the coin after the first said member has been actuated.

14. Coin controlled mechanism embodying a member to be actuated, an actuator independent thereof, a portion of said actuator being arranged in alinement with but spaced from said member, a pivotally mounted element, a portion of said element adapted to assume a position to receive and hold a coin in the space between said member and said actuator to form a connection between the member and actuator whereby the latter will actuate the former, a shoulder on said element adapted to be engaged and moved by one of the movable parts to shift said element to release the coin at a predetermined time in the cycle of operation of the device, and friction creating means operating upon said element for yieldingly retarding the movement of said element in one direction.

15. Coin controlled mechanism embodying a locking device, an actuating member for said device, an actuator independent of said member, a shiftable coin holder operating to position a coin between said member and said actuator whereby when said actuator is operated said member will be actuated to release said locking device, said coin holder being responsive in its operation, at a predetermined time in the cycle of operation, to the operation of said actuator to release the coin, and means for temporarily restraining said actuating members against return movement.

16. Coin controlled mechanism embodying a locking device, an actuating member for said device, an actuator independent of said member, a shiftable coin holder operating to position a coin between said member and said actuator whereby when said actuator is operated said member will be actuated to release said locking device, said coin holder being responsive in its operation, at a predetermined time in the cycle of operation, to the operation of said actuator to release the coin, and means for locking said actuating member against return movement, the last recited means being responsive in its operation to the operation of said actuator.

17. Coin controlled mechanism embodying a locking device, an actuating member for said device, an actuator independent of said member, a shiftable coin holder operating to position a coin between said member and said actuator whereby when said actuator is op-

erated said member will be actuated to release said locking device, said coin holder being responsive in its operation, at a predetermined time in the cycle of operation, to the operation of said actuator to release the coin, a locking device for locking the said actuating member against return movement, and means operatively connected with said actuator for rendering said locking means inactive.

18. Coin controlled mechanism embodying a locking device, an actuating member for said device, an actuator independent of said member, a shiftable coin holder operating to position a coin between said member and said actuator whereby when said actuator is operated said member will be actuated to release said locking device, said coin holder being responsive in its operation, at a predetermined time in the cycle of operation, to the operation of said actuator to release the coin, a catch for restraining the actuating member against return movement, and means responsive to the operation of said actuator for causing said catch to become active and inactive at predetermined times in the cycle of operation of said actuator.

19. Coin controlled mechanism embodying a locking device, an actuating member for said device, an actuator independent of said member, a shiftable coin holder operating to position a coin between said member and said actuator whereby when said actuator is operated said member will be actuated to release said locking device, said coin holder being responsive in its operation, at a predetermined time in the cycle of operation, to the operation of said actuator to release the coin, a catch for locking said actuator member against return movement, means tending normally to render said catch active, a cam surface connected with said catch, and means connected with said actuator and co-operating with said cam to render said catch active and inactive.

In testimony whereof we have signed our names to this specification on this 21st day of September, A. D. 1928.

LOUIS KAPLAN.
GEORGE WEISS.
